UNITED STATES PATENT OFFICE.

JOHN O. NEIKIRK, OF MORGAN PARK, ILLINOIS, ASSIGNOR TO RODGER BALLAST CAR COMPANY, A CORPORATION OF MAINE.

RAILWAY-CAR.

1,112,644.

Specification of Letters Patent.

Patented Oct. 6, 1914.

Application filed July 27, 1909. Serial No. 509,860.

To all whom it may concern:

Be it known that I, JOHN O. NEIKIRK, a citizen of the United States, residing at Morgan Park, in the county of Cook and 5 State of Illinois, have invented certain new and useful Improvements in Railway-Cars, of which the following is a specification.

The object of my invention is to provide an improved underframe construction possessing the advantages of strength and simplicity of structure.

I have illustrated my invention in connection with a car of the type known as the Hart convertible Rodger ballast car and 15 some of the features of my invention are especially adapted thereto. Some features of construction described, however, are adapted for use in cars of other types.

The nature and objects of my invention 20 will more fully appear from the specification and claims taken in connection with the accompanying drawings, in which—

Figure 1 is a plan view partially in section of the end portion of the car underframe 25 constructed according to my invention. Fig. 2 is a central longitudinal section of the end portion of the car. Fig. 3 is a perspective view of the bolster and related parts of the underframe. Fig. 4 is a perspective view of 30 a flanged web forming part of the bolster.

The car illustrated is provided with an underframe comprising continuous side sills 6 and continuous intermediate sills 7. The longitudinal hopper bottom 8 is located between the intermediate sills 7 and between the bolsters 2. The bolster comprises flanged webs 2 shown in detail in Fig. 4, and as illustrated in Fig. 1, the webs 2 extend continuously from one intermediate longitudinal sill 7 to the other and are secured thereto by rivets. The center sill or draft timbers 9 are secured to one of the webs 2 and extend outwardly therefrom to the end of the car. In the present instance the center sill consists of two channel beams secured to the web 2 by means of angle irons 10. Between the webs 2 are flanged plates 11 which form a continuation of the center sill. Secured to the lower side of the lower flange of 45 the channels forming the center sill are gusset plates or stiffeners 3. Between the gusset plates 3 and lower flanges of the web 2 is a lower cover plate 4 at its outer edges secured to the intermediate sills 7. The flange 50 on the web 2 is secured to the cover plate 4

and gusset 3 by rivets. The cover plate 4 extends inwardly from the bolster and near its inner edges is reinforced by an angle iron 12. Extending from the inner web 2 to the cover plate 4 are braces 13 each consisting of 60 a triangular piece of metal provided with horizontal and vertical flanges which are secured to the cover plate 4 and inner web 2, respectively. Between the outer ends of the webs 2 are located angular reinforcements in 65 the form of U-shaped metal braces 14 secured to said webs and to the intermediate sills. The end flanges of the webs 2 are also secured to the intermediate sills by means of rivets which also pass through the flanges 70 of webs 15 which extend between the intermediate and side sills. The part of the intermediate sills 7 between the bolster and end of the car consists in the present instance of a single built-up 75 channel having outwardly directed flanges. Inwardly from the bolster, however, the intermediate sills 7 consist of built-up I-beams, and a transverse timber 7' resting upon the lower inner flanges of the intermediate sills 80 affords support for the end of the hopper. The lower part of the end of the hopper is supported by straps 16 secured at their upper ends to the timber 5.

The end of the underframe beyond the 85 bolster may be stiffened by means of diagonal braces 17 extending from a gusset plate 18 secured to the end and center sill to the upper cover plate 1. The upper cover plate 1 extends continuously from side to side of 90 the car and is riveted to all of the longitudinal sills and to the upper flanges of the bolster webs 2.

I claim:

1. In a car underframe, continuous side 95 and intermediate sills extending from and secured to the end portion of said car underframe, a bolster extending continuously between said intermediate sills and articulated between said intermediate and side 100 sills, and a center sill extending between and secured to said bolster and the end portion of said car underframe, said bolster having integral end flanges secured to said intermediate sills and said side sills. 105

2. In a car underframe, side sills, intermediate sills, and a center sill, all being rigidly connected to and extending from the end portion of the car underframe, a bolster comprising webs having flanges integral 110

therewith, said bolster extending continuously from one intermediate sill to the other, an upper cover plate secured to said flanges and extending from one side sill to the other, 5 gusset plates secured to and extending outwardly from said center sill, and under cover plates secured to said gusset plates, flanges and intermediate sills.

3. In a car underframe, side sills, intermediate sills, and a center sill, all being rigidly connected to and extending from the end portion of the car underframe, a bolster comprising webs having flanges integral therewith, said bolster extending continuously from one intermediate sill to the other, an upper cover plate secured to said flanges and extending from one side sill to the other, 15 gusset plates secured to and extending outwardly from said center sill, under cover plates secured to said gusset plates, flanges and intermediate sills, and diagonal braces secured to and extending from the bolster to the end of the car underframe.

4. In a car, side, intermediate and center sills, all being rigidly connected to and extending from the end portion of the car underframe, a bolster comprising webs having flanges integral therewith, said bolster extending continuously from one intermediate 25 sill to the other, a lower cover plate, said center sill being secured to and extending outwardly from said bolster, said flanged webs being connected to said intermediate sills by U-shaped braces and by said integral flanges, and gusset plates secured to 30 said center sill and lower cover plate, said gusset plates, flanged web and lower cover plates being secured together, and said cover plate being secured to said intermediate sills.

40 5. In a car, side, intermediate and center sills, a bolster comprising webs having flanges integral therewith, said bolster extending continuously from one intermediate sill to the other, a lower cover plate, said center sill being secured to and extending outwardly from said bolster, said webs being connected to said intermediate sills by U-shaped braces and by said flanges, and gusset plates secured to said center sill and lower 45 cover plate, said gusset plates, web flanges

and lower cover plates being secured together, and said cover plates being secured to said intermediate sills, and the portion of said intermediate sills between the bolster and the proximate end of car underframe 55 consisting of single built-up channels, and the portion of said intermediate sills extending inwardly of said bolster consisting of built-up I-beams.

6. In a car underframe, continuous side 60 and intermediate sills extending from and secured to the end portion of said car underframe, and a bolster extending continuously between said intermediate sills and articulated between said intermediate and side 65 sills, said bolster comprising web portions having end flanges integral therewith both in its intermediate and in its articulated portions, said flanges being secured to said sills.

7. In a car underframe, continuous side 70 and intermediate sills extending from and secured to the end portion of said car underframe, a bolster extending continuously between said intermediate sills and articulated between said intermediate and side sills, said 75 bolster comprising web portions having end flanges integral therewith both in its intermediate and in its articulated portions, said flanges being secured to said sills, and U-shaped metal braces secured to said intermediate portions and to said intermediate sills.

8. In a car underframe, continuous side 80 and intermediate sills extending from and secured to the end portion of said car underframe, a bolster extending continuously between said intermediate sills and articulated between said intermediate and side sills, said 85 bolster comprising web portions having top and bottom flanges integral therewith, an upper cover plate secured to said upper flanges and extending from one side sill to the other, and a lower cover plate secured to said lower flanges and extending from one intermediate sill to the other.

In testimony whereof, I have subscribed 90 my name.

JOHN O. NEIKIRK.
